(57) **CLAIM**

The ornamental design for a tear-off flap for a container, as shown and described.

DESCRIPTION

FIG. 1 is a front perspective view of a tear-off flap for a container. The broken lines which define the bounds of the claimed design form no part thereof, and the dash dot lines representing portions of a container are for illustrative purposes only and form no part of the claimed design, FIG. 2 is a perspective view thereof,

FIG. 3 is an enlarged perspective view thereof,

FIG. 4 is an enlarged front view thereof,

FIG. 5 is an enlarged perspective view, seen from below,

FIG. 6 is a top plan view thereof; and,

FIG. 7 is an enlarged cross section thereof as seen along line 7—7 of FIG. 1.
